(57) **CLAIM**

The ornamental design for a window flashing product, as shown and described.

DESCRIPTION

FIG. 1 is a front perspective view of a first embodiment of the window flashing product, with an upper flap thereof in an open position, and indicating a portion thereof that is illustrated in detail in FIG. 3;

FIG. 2 is a front perspective view of the window flashing product of FIG. 1, with the upper flap in a sealed position; FIG. 3 is a front perspective detail view of a lower corner of the window flashing product of FIG. 1;

FIG. 4 is a front perspective view of a second embodiment of the window flashing product, with an upper flap thereof in an open position;

FIG. 5 is a front perspective view of the window flashing product of FIG. 4, with the upper flap in a sealed position; FIG. 6 is a side elevation of the window flashing product of FIG. 4, with the upper flap in the open position, an opposing side view being a mirror image thereof;

FIG. 7 is a top plan view of the window flashing product of FIG. 4, with the upper flap in the sealed position;

FIG. 8 is a bottom plan view of the window flashing product of FIG. 4, with the upper flap in the sealed position; and, FIG. 9 is a front perspective detail view of a lower corner of the window flashing product of FIG. 4.

In all of the drawings, broken lines indicate environmental structure that forms no part of the claimed design.

1 Claim, 7 Drawing Sheets
